United States Patent Office

Des. 185,763
Patented July 28, 1959

185,763

DISPLAY STAND FOR PACKAGED MERCHANDISE OR THE LIKE

Buford M. King, Jr., Northbrook, Ill., assignor to The Upjohn Company, Kalamazoo, Mich., a corporation of Michigan

Application August 21, 1957, Serial No. 47,463

Term of patent 14 years

(Cl. D80—9)

fig. 1

Figure 1 is a perspective view of a display stand for packaged merchandise or the like embodying my new design; and

The dominant features of the design reside in the portions shown in full lines.

I claim:

The ornamental design for a display stand for packaged merchandise or the like, as shown and described.
